UNITED STATES PATENT OFFICE

FRED L. KILLIAN, OF AKRON, OHIO

APPARATUS FOR MANUFACTURING THIN RUBBER ARTICLES

Application filed August 9, 1928. Serial No. 298,578.

This invention relates to new and novel improvements in apparatus for manufacturing thin rubber articles by the dipping process.

Broadly stated, objects of the invention are to provide a device of simple construction which may be operated to produce dipped rubber goods of uniform construction and which will eliminate in large part a number of manual operations heretofore considered necessary.

A further object is to provide a new and improved means for supporting forms whereby the same may be carried through the successive steps necessary to the complete production of rubber articles by the dipping process, without removing the forms from the supporting means.

The invention provides a form support composed of a plurality of hingedly connected bars which may be folded into a compact bed to collectively present the same to certain steps in the process of manufacture and which may be extended to successively present each article to certain other steps of manufacture without removing the forms from the support.

The invention also provides new and novel means for holding the form supports in a compact bed and new and novel means for automatically folding and unfolding the form supports.

In the drawings there is illustrated one form of the invention, it being understood that the invention is not confined to the particular form shown, but is capable of various adaptations and is subject to changes and modifications which come within the spirit of the invention as set forth in the claims hereunto appended.

In the drawings like characters of reference are employed to designate like parts as the same may appear in any of the several views and in which:

Figure 1 is a plan view illustrating a bead rolling device with a form holding means constructed in accordance with this invention, in operative engagement therewith;

Figure 2 is a side elevational view of same;

Figure 3 is a fragmentary view showing in side elevation the end portion of a form sup-

porting bar constructed in accordance with this invention, the same being shown with forms operatively mounted thereon,

Figure 4 is a plan view with parts broken away showing the form holding bars and illustrating the manner in which the same are connected,

Figure 5 is a view in end elevation of a bead rolling device illustrating the manner in which the form holding bars are presented thereto, the form holding bar and a part of the form being shown in vertical cross section,

Figure 6 is a view somewhat diagrammatic in character illustrating parts of the driving mechanism and bar engaging means used in reducing the invention to practice,

Figure 7 is a cross sectional view of a form mounted on a form carrying bar constructed in accordance with this invention.

In the particular adaptation of the invention shown, the numeral 10 is used generally to denote a form rack and the numeral 11 a bead rolling device such as is illustrated and described in my former Patent No. 1,605,445 which issued November 2, 1926. The numeral 12 denotes an improved form supporting bar which is preferably of a length adapted to be received in one of the form racks 10 as hereinafter described. Each bar 12 comprises an elongated body terminating at each end thereof in an enlarged head 13. The head 13 is provided with a horizontal slot 14 which extends therein from the outer end thereof for a purpose presently to appear,

Each head 13 is substantially wider than the main body of the bar 12 thereby providing inwardly presented square shoulders 15 at each end of the bar. The shoulder 15 is adapted to be engaged by means of operatively conveying the bars through the several processes of manufacture hereinafter described.

Each bar 12 is provided on the upper face thereof with a plurality of cylindrical bosses 16 which are positioned in spaced relation thereon in a longitudinally directed row. Each boss 16 is provided with a suitable bore 17 which projects axially therethrough and extends through the body of the bar 12. A pin 18 is rigidly secured in each bore 17.

The numeral 19 denotes a form which may be of any desired construction and which is provided on the lower end thereof with an axial bore 20 adapted to receive one of the pins 18. Each form is provided with a groove 5 21 which extends therearound in a plane in spaced relation to the lower end thereof. The numeral 22 denotes brackets which are secured to the upper face of each bar 12 by means of the rivets 23 or other suitable 10 means. Each bracket 22 terminates at the upper end thereof in a horizontal portion which is entered in one of the slots 21 whereby each form 19 is retained in position on one of the pins 18. It will thus be seen that each 15 of the bars 12 is provided with a plurality of forms which are rotatably secured thereto in a longitudinally directed row.

The numeral 24 denotes a link which is provided adjacent each end thereof with a 20 suitable bore 25. The head 13 is likewise provided at a point centrally thereof with a vertical bore 26. Each end of each link 24 is operatively positioned in one of the slots 14 with the bore 25 coinciding with the bore 26 25 in the head 13. A pin 27 which is somewhat similar to the pins 18 is positioned through the bores 25 and 26, to hingedly secure each end of each link 24 in one of the heads 13. It will thus be seen that a plurality of bars 30 may be thus connected and that each bar will have a free swinging movement relative to the adjacent bar.

It will thus be seen that a plurality of bars 12 may be connected by means of the 35 links 24 to form a long chain which may be employed to successively present the forms 19 to certain steps in the process of manufacture, and that the bars 12 may be folded as 40 shown in Figure 1 to form a compact bed for the purpose of conveying the forms from one operation to the other or for collectively submitting a large number of forms to one operation.

The frame 10 is employed to support the 45 members 12 to hold the same in a compact bed and may be of any suitable construction. The frame 10 as shown in the drawings is provided on each of its four sides with a hinged member 10a which may be swung upwardly 50 to enclose the bars 12. Each member 10a is provided at the outer edge thereof with the flange 10b which is adapted to project over the end portion 13 of the bars 12 when the members 10a are swung to an upright position 55 thereby providing means for retaining the members 12 on the frame 10. The end members 10a are provided on each end thereof with an ear 10c which is arranged to overlap 60 the ends of the side members to retain the same in an upright position. Any suitable fastening means such as the pin 12d is employed 65 to hold the four end members 10a in an upright position, thus securely retaining the bars 12 in a compact bed. With the

frames folded and thus locked in position on the frame 10, the entire frame is positioned in the dipping machine which may be of ordinary or improved construction and the forms 19 are coated with rubber by the well known dipping process. The bed 10 is then positioned on one of the trucks 28 and the same is conveyed to the bead rolling machine 11. The bead rolling machine 11 is provided with an ontake table 11a which is preferably composed of relatively thin sheet iron. The ontake table 11a is hingedly secured to the frame of the bead rolling machine 11 by means of the hinge 11b, and the outer end of the ontake table 11a is supported by means of the rods or cables 11c which extend to an overhead support (not shown). The table 11a is positioned in a horizontal plane immediately above the plane occupied by the frame 10 when positioned on the truck 28. The ontake table 11a is provided on the upper side thereof with the guide members 11d which are positioned a sufficient distance apart, at the outer edge of the table, to receive the length of the bars 12. The guide members 11d converge to the parallel guide members 11e on the machine 11, which are adapted to receive the bars 12 when the same are presented longitudinally thereto. The machine 11 is provided with a conveyor chain 11f which is mounted on the sprocket wheels 11g and 11h so as to extend longitudinally of the machine 11. A fork member 11j is positioned on the chain 11f to engage the shoulders 15 on the bars 12 and force the said bars longitudinally through the machine 11. The truck 10 is positioned at the outer edge of the ontake table 11a, with the side members 10a are folded downwardly and the first bar 12 is extended inwardly to a position where it is engaged by one of the fork members 11j. This forces the bar 11 through the guide slot 11k which extends longitudinally of the machine and subjects each form 19 to the action of a cylindrical brush 11n which is positioned longitudinally of the 110 guide slot 11k as is described in my former patent to which reference has been made.

It will be noted that the forms are thus driven longitudinally of the brush 11n and that the same are rotated by means of the belt 11m while in contact with the rotating brush 11n, thereby rolling the lower edge of a tubular rubber article positioned on said forms 19 upwardly and forming an annular bead on the open end thereof.

The numeral 11p denotes an offtake table which is similar to the ontake table 11a and is similarly secured thereto by means of the hinge 11b. A supporting member 11c is likewise employed to support the outer end of the offtake table 11p. The table 11p is provided with suitable guide members 11q which are similar to the guide members 11d on the table 11a. The guide members converge from the parallel guide members 11r on the machine 130

11. A truck 28 is positioned along the off-take table 23 and one of the end rails 10a is swung downwardly and secured in position to receive the first bar 12 as it is driven from the machine. As each successive bar is driven through the machine 11 by means of the chain 11f, the bars 12 are thus folded on the rack 10 on the truck 28 at the offtake end of the machine. As each bar 12 is added to the frame 10, the truck 28 is pushed forwardly on the wheels 28a until the entire chain of the connected bars 12 are folded to completely fill the frame 12. The side members 10a are then folded in position on the frame 10 and are driven through a vulcanizing chamber and through a steaming chamber. The frame is then positioned on a truck 28 and bars 12 are extended and passed through a take-off machine similar to the device shown and described in United States Letters Patent No. 1,483,664 granted February 12, 1924. The bars are again folded in one of the frames 10 and are positioned on one of trucks 28 and conveyed to the dipping tank.

25 The brush 11n is preferably positioned at an upward inclination to the path of the forms with the lower end thereof presented toward the ontake end of the machine. A construction is thus provided in which the brush will first engage the lowermost edge of the rubber article positioned on each form and will roll the same upwardly in accordance with the relative inclination of the brush and conveyor.

35 While the device 11 is illustrated and described as a bead rolling machine, it will be seen that the brush 11n operates to roll the lower edge of the rubber article upwardly on the form and that the size of the bead or roll is regulated by the inclination of the brush relative to the path of the rotating forms. It will thus be seen that the brush 11n may be set at an inclination which will cause it to contact with the full length of the 40 form 19 while the form is being driven longitudinally thereof, in which case the article will be entirely removed from the form. It is therefore considered unnecessary to illustrate the take-off mechanism as it is structurally the same as the bead rolling mechanism, differing only in minor details, such as the inclination of the brush 11n.

Obviously, each bar 12 may be provided with two rows of forms and the mechanism shown in the device 11 duplicated to provide a brush 11n and form rotating means 11m on each side of the conveyor 11f thereby providing means for simultaneously operating on two rows of forms.

60 It will thus be seen that I have provided a new and novel supporting means whereby forms may be locked in a compact bed and collectively submitted to certain operations which may be extended to successively submit each form to certain other operations.

Having thus illustrated my invention and described the same in detail, what I claim as new and desire to secure by Letters Patent is:—

1. In a form support, a plurality of bars, a plurality of forms carried by each bar and hinge means connecting said bars in end to end relation, said means operable to permit said bars to be extended in a line or folded in the form of a rectangular bed. 75

2. In a form support, a plurality of bars, means to connect said bars in end to end relation whereby the same may be folded in a compact rack or extended in a line.

3. In a form support, a plurality of form supporting members, forms carried by each member, straps connecting said members, said straps being hingedly connected to each member for movement on a vertical axis. 80

4. In a form support, a plurality of form supporting members, forms rotatably mounted on each member and hinge means connecting said members in end to end relation. 85

5. In a device of the class described, a plurality of connected form supports, a plurality of forms rotatably mounted on each support, bead forming means and means actuating said form supports to operatively present said forms to said bead rolling means. 90

6. In apparatus for manufacturing thin rubber articles, bead rolling means, a plurality of connected form supporting members, a plurality of forms mounted on each member and means to successively move said members to bring said forms in operative engagement with said bead rolling means. 100

7. In apparatus of the class described, rotatable bead rolling means, form rotating means, a plurality of connected form engaging members, forms rotatably mounted on each member and means actuating said form carrying members to bring the forms in operative contact with said bead forming means. 105

8. In apparatus of the class described, bead forming means, a plurality of members, forms mounted on each member, means connecting said members and means to successively move said members to said bead forming means. 110

9. In apparatus of the class described, a rotatable brush, a plurality of connected bars, a plurality of forms mounted on each bar and means to successively move said bars relative to said brush to bring said forms in operative contact therewith. 115

10. In apparatus of the class described, a plurality of form carrying members, means to hingedly connect said members whereby the same may be extended in a line or folded to form a compact rack and means operable to hold the same in a folded condition. 120

11. In apparatus of the class described, in combination, a plurality of form carrying 125

130

members, means connecting said members whereby the same may be extended in a line or folded in parallel relation, a rack for holding said members in a folded position thereon and means operable to lock said members on said rack.

12. Apparatus of the class described comprising a series of members, each rotatably supporting a plurality of dipping forms arranged in a row, means hingedly connecting said members whereby the same may be extended in a straight line or folded in a compact bed, means to hold said members in a compact bed while the forms are dipped, means to operate on the forms, means for extending said members and conveying the same past said operating means and means for rotating said forms during the movement of said members past said operating means.

20 13. Apparatus of the class described, comprising a series of hingedly connected members, each rotatably supporting one or more forms, means for operating on the forms, means for rotating the forms while operated upon and means for conveying said members past the operating means and form rotating means.

30 14. Apparatus of the class described comprising a plurality of hingedly connected members, each rotatably supporting a plurality of forms, means for operating on the forms and means to convey said members past said operating means.

35 15. Apparatus of the class described, comprising a plurality of members, each supporting a plurality of forms, means to connect said members in end to end relation whereby the same may be folded for simultaneously dipping all of the forms in a rubber solution to form a rubber article thereon and extended in a line, means to operate on said rubber articles and means to convey said members in a line to present said articles to said operating means.

45 16. Apparatus of the class described, comprising a plurality of members each supporting a plurality of forms, means to hingedly connect said members whereby the same may be folded to form a compact rack or extended in a line, means to operate on said forms, means to unfold said members and drive the same in a line past said operating means and means to again fold said members in a compact rack after the same have been driven past said operating means.

In testimony whereof I have hereunto set my hand.

FRED L. KILLIAN.
